2,565,043

STOP MOTION MECHANISM FOR NARROW
FABRIC LOOMSWillis Pruitt, Attalla, Ala., assignor to Lawrence
Products Company, Inc., Attalla, Ala., a corpo-
ration of Alabama

Application December 30, 1949, Serial No. 136,044

10 Claims. (Cl. 139—371)

1

This invention relates generally to means for automatically stopping narrow fabric looms before the filling or weft thread is completely exhausted, and more particularly to an improvement over the structure disclosed in my prior Patent 2,456,021 issued December 14, 1948.

The primary object of this invention is to provide reliable, efficient, automatic means for stopping a narrow fabric loom before the weft thread is exhausted to thereby eliminate the danger of broken picks or weft threads, and thus prevent unevenness in the fabric and provide a more perfect product.

The continuation of the running of a loom with an empty shuttle causes damage to, or imperfections in, the woven fabric, and also causes loss or waste of yarn. In narrow fabric looms, such as those provided for weaving ribbon, a series of shuttles are simultaneously operated to produce a plurality of ribbons or other narrow fabrics, thus making observation of the exhaustion of the yarn on the bobbins in the shuttles more difficult.

It is therefore a further object of the present invention to provide electrical stopping means for narrow fabric looms enabling the machine to stop automatically as soon as the weft thread in one of the shuttles is near exhaustion.

Another object of this invention is to provide the shuttle with a metal quill, so that, when the yarn on the quill has about reached its state of exhaustion, electrical contact may be established between the quill and contacting means carried by the breast beam and intermittently engaging contacts on the shuttle, as the shuttle is reciprocated with the batten, to close an electric circuit controlling the starting mechanism of the loom.

Still another object of the present invention is to provide such automatic stopping means for narrow fabric looms in which the stopping mechanism is made up of a minimum of movable parts and may be adapted to the looms now in use without requiring substantial modification or change thereof.

These and other objects and certain advantageous features are accomplished by the novel and practical construction, combination and arrangement of parts hereinafter disclosed and illustrated in the accompanying drawings, constituting an essential part of the disclosure, and in which:

Figure 1 is a top plan view of a shuttle constructed according to this invention, and showing the contacts which are mounted upon the breast beam of the loom,

2

Figure 2 is an end view of the shuttle illustrated in Figure 1.

Figure 3 is a front elevational view of the shuttle illustrated in Figure 1, with the portion 5 of the breast beam disposed in front of the shuttle cut away.

Figure 4 is a side view of the contact supporting bracket secured to the breast beam, with the front edge of the shuttle shown in fragmentary 10 form,

Figure 5 is a diagrammatic top plan view of a portion of the loom, embodying this invention, showing the relationship between the various 15 essential parts, including one shuttle and an empty shuttle position, and

Figure 6 is an electrical diagram including a modified form of quill contact finger.

In the conventional narrow fabric loom a plurality of shuttles are simultaneously operated 20 to produce a plurality of ribbons or other narrow fabrics. Only part of such a machine is shown in the drawings, covering only the essential parts of this invention.

Referring initially to Figure 5, a conventional 25 narrow fabric loom is there illustrated, having the batten 15, to which are secured the supports 16 for the upper and lower shuttle blocks 17. The shuttle 18 is guided within the shuttle blocks 17, and is moved by means of the gear rack 19 30 meshing with the pinions 20, in a manner more fully disclosed in my patent noted above. In any event, moving the rack 19 in the direction of the arrow 21, will cause the shuttle 18 to move to the direction of the arrow 22, these movements 35 being then reversed, thus weaving the narrow fabric in the conventional manner. The rack 19 is reciprocated longitudinally by means of the strap 23 trained over the pulleys 24 and 25, which in turn are connected to a shuttle motion drive 40 (not shown).

The warp threads W come from the warp beam 26, rotatably mounted on the framework of the machine, and are extended through the heddles, not shown, of the harnesses 27 and 28 which are 45 reciprocated vertically in a conventional manner. After passing through the heddles of the harnesses 27 and 28, the warp threads W are extended through the reed 29 clamped to the batten 15, and hence forwardly over the take-up beam S. The batten 15 is rocked forwardly and rearwardly with respect to the breast beam 30 by means of the connecting rod 31 pivotally secured by the bracket 32 to the batten 15 and also pivotally connected to the eccentric crank 33 of 50 the rotatable crank shaft 34.

In the conventional operation of the loom illustrated in Figure 5, the shuttle 18, carrying the thread wound quill 35 moves forwardly and rearwardly in accordance with the movement of the batten 15 and also moves transversely reciprocatingly in accordance with the movement of the rack 19, and in the shed formed between the two layers of V-formed intertwined warp between the two adjacent pairs of shuttle blocks 17. During this transverse movement, the shuttle 18 slides along the shuttle block 17, in which it is seen in Figure 5, through the warp shed across the warp threads and into the adjacent shuttle block 17 which is shown in an empty condition in the illustration. A layer of warp threads carried by one gang of heddles (not shown) on one harness 27 is then moved with the latter relative to the layer of warp threads carried by the heddles (not shown) on the other harness 28, one layer of warp threads meshing with the other layer of warp threads, and holding the weft thread T wound on the quill 35 and carried across by the shuttle 18, between the threads of the layers. The shuttle 18 then reverses in direction and returns to the original shuttle holder laying another weft across the forming fabric F, the direction of movements of the harnesses 27 and 28 being reversed. This operation, described above, is conventional in narrow fabric looms.

The shuttle 18, of this invention is similar to that set forth in my prior Patent No. 2,456,021, with the exception of the means provided for establishing electrical contact for stopping the loom. The shuttle 18 is provided with an electrically conducting metal quill 35, which is rotatably supported on the quill shaft 36. The opposite ends of the quill shaft 36 are carried within the metallic electrically conducting bushings 37 and 38. The contacting lever 39 is rockably mounted at one end within the metallic bushing 40 embedded within the shuttle frame. The other end of the lever 39 is formed with a looped member 41 for engagement with the surface of the metal quill 35. A cantilever resilient spring member 42 has one end 43 thereof embedded within the shuttle frame, and is formed with a hook 44 at the other end for engagement with the lever 39. As can be seen in Figure 1, the resilient spring member 42 constantly urges the lever 39 to rock towards the quill 35. A pair of spaced apart metal staples are driven into the forward end of the shuttle frame 18 and are indicated by the numerals 45 and 46. The staples 45 and 46 are provided each with an elongated leg 47 and 48 respectively which extend through the heddle frame for attachment to electrical conductors. The electrical conductor 49, embedded within the shuttle frame, is electrically connected at its opposite ends to the bushing 37 and the leg 47 of the staple 45. The electrical conductor 50, similarly embedded within the shuttle frame, is connected at its opposite ends to the bushing 40 and the leg 48 of the staple 46. Brackets 51, having bifurcations 52 and 53 on the lower end thereof, are secured to the breast beam 30 of the loom in positions confronting each of the shuttle supports or holders 17. The set screw 54, threadably engaging through the bifurcation 53, bears against the breast beam for retaining the bracket 51 in its selected position. Each bracket, as seen in detail in Figure 4, includes an upstanding portion 55 having a bore 56 formed through the top thereof. A contact supporting rod 57 is slidably disposed within the bore 56, and is engaged by the set screw 58

so as to be held in selected position relative to the bracket 51. The supporting rod 57 extends rearwardly towards the reciprocatable batten 15, and an insulating block 59 extends transversely of the rear end of the rod 57 and is secured to the threaded reduced diameter extension 60 of the rod by the nut 61 threaded thereon. Resilient contact fingers 62 and 63 depend from each of the opposite ends of the rear face of the insulating block 59, and are secured to the latter by the fastening means 64 and 65 respectively.

Electrical conductors 66 and 67 are connected to the resilient spring fingers 62 and 63 respectively by attachment to the fastening means 64 and 65. As seen in Figure 5, the conductor 66 connects through the transformer 68 and the conductor 66a to one terminal of the electromagnet 69 of a relay 70. The other conductor 67 is connected to the other terminal of the electromagnet 69. The auxiliary contact 71 of the relay 70 is connected to one terminal of a magnetic starter 72 by the wire 73. The wire 74 connects another terminal of the magnetic starter 72 to the pivoted arm 75 of the relay 70. The conductors 73 and 74 connect with the motor leads 76 through the magnetic starter 72. The relay and magnetic starter set forth above are conventional.

The transverse movement of the shuttle 18 is so coordinated with the forward and rearward movement of the batten 15 as to dispose the shuttle in either one of the shuttle holders 17 when the batten is in its full forward position. As seen in Figure 5, when the batten is in its full forward position the staples 45 and 46 carried by the shuttle 18 will engage the contact fingers 62 and 63. If the thread T on the quill 35 in the shuttle is used up to such an extent that the looped portion 41 of the lever 39 engages the bare metal surface of the quill 35, then a closed electrical circuit will be established through the electromagnet 69, the conductor 67, the contact finger 63, the staple 45, the wire 49, the bushing 37, the quill 35, the lever 39, the bushing 40, the wire 50, the staple 46, the resilient contact finger 62, and the conductor 66, the transformer 68, and the conductor 66a back to the electromagnet 69. The electromagnet 69 will thereby be energized, causing the switch arm 75 to be attracted and moved away from the auxiliary contact 71 of the relay, thus breaking the motor circuit controlled by the magnetic starter 72. After the quill 35 has been replenished with thread, the machine is again started in a conventional manner.

Although it is preferable to employ a pair of resilient contact fingers, such as 62 and 63 to indicate when another full quill is required, one contact finger may be employed by grounding the metal quill, or the contacting lever 39 to the frame structure of the machine, and also grounding one of the terminals of the electromagnet 69 of the relay 70. Figure 6 shows such a modified arrangement. In this latter case, the spring pressed contacting lever 39a, engageable with the quill 35a within the shuttle 18a is connected to ground by the conductor 66c and the quill 35a is connected to the single contact staple by a conductor 49a. The conductor 66b extends from one terminal of the electromagnet 69a of the relay 70a to ground, and the single contact finger 63a is connected to the transformer 68a by the conductor 67a. As in the first embodiment, the relay 70a controls the energization of the motor operating the loom through the magnetic starter 72a.

The arrangement set forth for providing an automatic stopping device is adapted to single

and double decker battens, that is, looms in which several superimposed layers of shuttles are provided. I have illustrated in broken lines in Figure 4, the manner in which the structure may be modified to accommodate such double rows of shuttles. In this latter situation the top ends of the contacting fingers 62 will be extended upwardly as at 62' for engagement with the staples carried by the upper row of shuttles 18'.

From the above description it can readily be seen that I have provided automatic electrical means for stopping a loom of the type described when the thread on the quills have been exhausted and in which the movable parts are kept at a minimum to thereby minimize wear and provide for extended trouble free service. It is to be understood that various changes and modifications may be made in the specific structure described without departing from the scope of the invention as defined in the appended claims.

Having thus described the invention, what is claimed as new and desired to be secured by Letters Patent is:

1. On a narrow fabric loom having electrical starting and stopping means and including a breast beam, a batten movable toward and away from said breast beam and a shuttle mounted for reciprocation laterally on said batten; stop motion comprising an electrically conducting quill member upon which weft thread may be wound and carried by said shuttle, an electrically conducting rockable member on said shuttle constantly urged towards engagement with said quill member, contact means on said shuttle connected in series with said quill member and said rockable member, second contact means carried by said breast beam of the loom and adapted to electrically engage said first contact means when the shuttle is carried by said batten to the foremost position thereof, and means connecting said second contact means with said electrical starting and stopping means whereby an electrical circuit will be closed through said quill member, said rockable member, said first and second contact means, and said last mentioned means when the weft thread on said quill member is exhausted to permit electrical contact between said rockable member and said quill member.

2. On a narrow fabric loom having electrical starting and stopping means and including a breast beam, a batten movable toward and away from said breast beam and a shuttle mounted for reciprocation laterally on said batten; stop motion comprising an electrically conducting quill carried by said shuttle and upon which weft thread may be wound, a rockable electrically conducting lever carried by said shuttle and spring urged towards said quill for electrical contact with the latter when the weft thread is exhausted, first contact means on said shuttle electrically connected in the circuit formed when said quill and lever are in electrical contact, second contact means carried by said breast beam of the loom and engaging said first contact means when said shuttle is carried by said batten to the foremost position, and conducting means connecting said second contact means with said electrical starting and stopping means.

3. On a narrow fabric loom having electrical starting and stopping means and including a breast beam, a batten movable toward and away from said breast beam and a shuttle mounted for reciprocation laterally on said batten; stop motion comprising an electrically conducting quill carried by said shuttle, means on said shuttle

adapted to electrically contact said quill when the weft thread on the latter is exhausted, a pair of contact members on said shuttle electrically connected to said quill and said last named means, a second pair of contact members carried by said breast beam of the loom and adapted to intermittently engage said first pair of contact members, and conductors extending between said second pair of contact members and said electrical starting and stopping means.

4. On a narrow fabric loom having electrical starting and stopping means and including a breast beam, a batten movable toward and away from said breast beam and a shuttle mounted for reciprocation laterally on said batten; stop motion comprising an electrically conducting quill upon which weft thread may be wound and carried by said shuttle, means on said shuttle electrically contacting said quill when the thread on the latter is exhausted, contact means on said shuttle and on said breast beam of the loom adapted to electrically engage when the shuttle is carried by the batten to the foremost position thereof, means electrically connecting said quill and said means on said shuttle to said contact means on said shuttle, and means electrically connecting said contact means on said breast beam to said starting and stopping means.

5. Stop motion according to claim 4, wherein said means on said shuttle electrically contacting said quill when the thread on the latter is exhausted includes a lever having one end rockably carried by the shuttle and a portion on the other end engageable with the center of said quill, and spring means carried by said shuttle and engaging said lever urging said portion against said quill.

6. Stop motion according to claim 4, wherein said contact means on said shuttle includes a pair of spaced apart staples having portions thereof projecting from the forward end of the shuttle for contact with the contact means on the breast beam.

7. On a narrow fabric loom having electrical starting and stopping means and including a breast beam, a batten movable toward and away from said breast beam and a shuttle mounted for reciprocation laterally on said batten; stop motion comprising an electrically conducting quill carried by said shuttle and upon which weft thread may be wound, a contact lever rockably carried by said shuttle, spring means constantly urging said lever towards said quill whereby said lever will electrically contact said quill when the thread on the latter is exhausted, a pair of spaced apart contact members carried by the forward end of said shuttle, electrical connecting means extending between said quill and one of said contact members and between said lever and the other of said contact members, a contact support secured to said breast beam of the loom, a pair of spaced apart contact members carried by said support and adapted to engage said contact members on said shuttle when said batten is disposed in the foremost position thereof, and electrical connecting means extending between said latter pair of contact members and said electrical starting and stopping means.

8. Stop motion according to claim 7, wherein said contact support includes an upstanding member, a rod slidably carried adjacent the top of said member and movable in the direction of the reciprocation of the batten, an insulating block fixed to the rear end of said rod and extending transversely thereof, said block carrying said sec-

ond pair of contact members at the opposite ends thereof.

9. On a narrow fabric loom having a magnetic starter provided with a relay and including a forwardly and rearwardly moving batten and a shuttle mounted for lateral reciprocation on the latter; stop motion comprising an electrically conducting quill upon which weft thread may be wound, said quill being carried by said shuttle mounted on the batten, a rockable contact lever carried by the shuttle and constantly urged towards said quill for establishing electrical contact with the latter when the weft thread is exhausted, electrical conducting means connecting said quill to one side of said relay and said contact lever to the other side of said relay when said batten is disposed in the foremost position thereof, and a transformer interposed in said conducting means for energizing said relay.

10. Stop motion according to claim 9 wherein the loom further includes a breast beam in front of said batten and said electrical conducting means includes contact members carried by said shuttle and by the breast beam of the loom engaging when the batten is advanced towards said breast beam.
